CLAIM

The ornamental design for a bag, as shown and described.

DESCRIPTION

FIG. 1 is a perspective view of a bag showing my new design in a first embodiment;

FIG. 2 is a front side view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of a bag showing my new design in a second embodiment;

FIG. 9 is a front side view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken lines showing carrying straps in FIGS. 1-6 and FIGS. 8-13 depict environmental structure and form no part of the claimed design. The broken lines depict portions of the bag that form no part of the claimed design.

1 Claim, 12 Drawing Sheets
